Williams, the subscriber of the said, do avow to The Union Steamship Company,
Letter Patent No. 2501, dated Oct. 30, 1866.

Design for a Trade Mark:

the Schedule of Serials in the Letter Patent and making part of the same
where it may concern.

Be it known that of Williams, the subscriber of the said, in the County
of St. Louis in the State of Missouri, have originated or invented a new, and
original Design for a Trade Mark, and I hereby declare the following to be a full
and exact description of the same, after naming the accompanying
drawing.

The Design thus named is intended as a Trade Mark, which
designates as the "Original Oliver Branch."

A branch of a tree flying in the air holding a blue branch,
around the design is the name of the firm to whom the branch belongs, may bear
any name, but the name "Original Oliver Branch" is the name
of this branch; the whole design and lettering being enclosed, if delivered within
ascertained space or border.

Having distinctly invented what I claim and desire to secure by Letter Patent is,
The Design for a Trade Mark as herein shown and described.

As testimony whereof, I have signed my name to this
specification, before this 25th day of October, A.D. 1866.

Witnesses.
